UNITED STATES PATENT OFFICE

OTTO ANGELL GRÖNBERG, OF OSLO, NORWAY

HANGER FOR AIR CABLES

Application filed December 11, 1926, Serial No. 154,152, and in Norway December 22, 1925.

The present invention has for its object a hanger for air cables comprising a metal strip, the opposite ends of which are bent so as to form two loops, one of which is adapted to fit the carrying wire, whereas the other is adapted to fit the cable. Between the loops the strip is preferably given a curved or angular cross section. The free ends of the strip is formed to correspond with the middle part thereof and is provided on both sides with hooks or loops adapted to slip over the edges of the middle part by being pressed against the same. The angular or curved sides of the middle part press the hooked part of the ends outwards so that they finally slip over the edges. The hooks may also be formed on the middle part and being adapted to grip over the edges of the ends although the first mentioned form is preferred.

On the drawing Fig. 1 is an end view of the hanger, the same being illustrated with full lines in the closed position and with dotted lines in its open position.

Fig. 2 is a view of the hanger seen from the left hand side of Fig. 1.

Fig. 3 is a view as seen from the right hand side of Fig. 1, and Fig. 4 is a cross section on the line IV-IV on Fig. 2.

As will be seen the metal strip A is bent at B to form a loop fitting the carrying wire C and at D so as to form a loop fitting the cable E. The middle part is given an angular cross section, as seen on Fig. 4 and the same cross section is given to the free ends G and H of the metal strip. The free ends are also provided with hooks I, adapted to slip over and grip the edges of the angular middle part F when pressed against the same, thereby locking the hanger in its closed position.

As it will be understood the said hooks I may also be formed on the middle part, the ends being adapted to be placed towards the concave side of the same.

Claims:

1. A hanger for air cables formed from a single strip of resilient metal comprising a medial portion, loops continuing from the ends of the medial portion and adapted for

fitting a carrying wire and a cable respectively, end portions continuing from the loops and arranged adjacent the medial portion, and means for connecting each of the end portions independently with the medial portion, including tongues integral with and projecting from the lateral edges of one of said portions and engaging and gripping the lateral edges of the other adjacent portion.

2. A hanger for air cables as claimed in claim 1, wherein the lateral tongues are integral with the side edges of each of the two end portions of the hanger.

In testimony whereof I have signed my name to this specification.

OTTO ANGELL GRÖNBERG.
